United States Patent Office

Des. 182,937
Patented May 27, 1958

182,937

CAN OPENER

Henry J. Talge, Kansas City, Mo., and Frank E. Aberer,
Kansas City, Kans., assignors to John C. Hockery,
Kansas City, Mo., trustee

Application September 13, 1957, Serial No. 47,733

Term of patent 14 years

(Cl. D22—2)

Fig. 1.

Fig. 2.

Fig. 3.

Fig. 1 is a front elevational view of a can opener embodying our new design;

Fig. 2 is a side elevational view of same;

Fig. 3 is a top plan view of same;

Fig. 4 is a bottom plan view of same;

Fig. 5 is a bottom plan view of same, showing the legs in folded position;

Fig. 6 is a rear elevational view of same, shown with the legs folded; and

Fig. 7 is a side elevational view, shown with the legs folded, this view being taken from the side opposite that shown in Fig. 2.

The essential features of our design reside in the portions shown in solid lines on the drawing.

We claim:

The ornamental design for a can opener, as shown and described.
